Attorney

UNITED STATES PATENT OFFICE.

OTTO JOHN BOETTCHER, OF MANITOWOC, WISCONSIN.

DRAW-PRESS.

1,366,513.

Specification of Letters Patent. Patented Jan. 25, 1921.

Application filed May 24, 1920. Serial No. 383,892.

To all whom it may concern:

Be it known that I, OTTO J. BOETTCHER, a citizen of the United States, residing at Manitowoc, in the county of Manitowoc and 5 State of Wisconsin, have invented certain new and useful Improvements in Draw-Presses, of which the following is a specification.

This invention relates to presses for drawing sheet metal shells and other similar articles by means of drawing punches and dies; and it consists in the novel construction and combination of the parts forming an attachment for the press as hereinafter fully 15 described and claimed.

In the drawings, Figure 1 is a front view of portions of a press provided with an attachment according to this invention, some 20 of the parts being shown in section. Fig. 2 is a sectional plan view of the crosshead or ram, taken on the line 2-2 in Fig. 1.

The press is provided with a frame 3 having a stationary horizontal press bed 4 at its lower part. The crosshead or ram 5 of the 25 press, which carries the drawing punch 6, is slidable in vertical guides 7 on the frame, and is reciprocated by means of a connecting-rod 8 and any suitable driving mechanism, all of these parts being of any approved construction.

In re-drawing light metal shells, and other similar articles, in presses of this sort, the shells sometimes buckle-up, wrinkle and tear, and the attachment hereinafter described is adapted to overcome these drawbacks, and improve the efficiency of the 35 machine.

Supporting bars 9 are rigidly secured to the underside of the crosshead 5, and project horizontally at the front and rear of the machine. Vertical rods 10 are arranged to slide in holes 11 in the bars 9, and have screwthreaded portions 12 at their upper ends. Nuts 14 are screwed on the rods 10 40 above the bars, so that the rods are suspended from the bars 9, and jam nuts 15 are provided for locking the nuts 14 after the rods 10 have been adjusted in length.

The lower end portions of the rods 10 are 50 provided with extension rods 16, and a sleeve holder 17 is secured to the rods 10 where they are connected to the extension rods 16. The sleeve holder 17 extends diagonally under the crosshead 5 of the press, and 55 is arranged horizontally. The extension rods 16 may be solid metallic rods if desired,

or they may be formed of steel tubes for lightness, when preferable. The rods 10 have screwthreaded portions 18 at their lower ends which are screwed into the upper 60 end portions of the extension rods 16, and collars 19 are provided on the rods 10, so that the sleeve holder 17 is clamped between the collars 19 and the upper ends of the extension rods. The sleeve holder may however be rigidly connected to the rods 10 in any other approved manner.

A tubular sleeve 20 is secured to the middle part of the sleeve holder and has a beveled portion 21 at its lower part. The drawing punch is slidable in this sleeve, and in a hole 23 in the sleeve holder. A suitable die 22 is secured to the press bed for the drawing punch to engage with in the usual manner. The sleeve 20 slides vertically 75 with the crosshead 5 and the drawing punch 6, but the crosshead and punch have a longer stroke than the sleeve. The punch 6 slides downwardly in the sleeve when the latter is held stationary by contact with the 80 work.

The extension rods 16 are slidable vertically in holes 24 in the press bed, and they have screwthreaded portions 25 at their upper parts. Split nuts 26 are screwed on the 85 parts 25 above the press bed, and these nuts form stops as will be more fully explained hereinafter. The split nuts 26 may be dispensed with, if desired.

The extension rods 16 have screwthreaded 90 portions 28 at their lower ends, and are provided with adjusting nuts 29. Helical springs 30 are arranged around the lower parts of the extension rods 16 between the nuts 29 and the press bed, and 31 are centering washers which support the springs 30 95 on the extension rods.

When the various parts of the attachment have been put together as shown in the drawings, the nuts 14 are first adjusted 100 and are screwed downwardly on the rods 10 against the bars 9 until the bottom edge of the sleeve 20 is exactly flush with the bottom end of the drawing punch when in its raised position. The nuts 14 are then locked 105 by the jam nuts. The split nuts 26 are screwed upwardly on the rods 16 so that they will not strike the press bed 4 prematurely. The crosshead 5 is then lowered until the sleeve 20 comes in contact with the 110 die 22, and the split nuts are then adjusted by screwing them against the press bed so

that the sleeve is raised a little and is held away from the die at a distance equal to the thickness of the metal of the shell or other article to be drawn out. The nuts 29 are then screwed on the extension rods, so as to compress the helical springs to a predetermined extent, and the press is ready to operate.

The shell is placed between the die and the sleeve, when the sleeve and drawing punch are raised. As the crosshead is forced down, the sleeve enters the shell and slides downwardly until it presses the shell against the die. The springs 30 are placed under considerable tension or compression when the crosshead 5 is raised, and they press the nuts 14 on the supporting bars 9 until the beveled end 21 of the sleeve 20 bears on the shell. The springs 30, or other equivalent operating means, then hold the shell pressed against the stationary die with a constant and uniform pressure. This pressure prevents the shell from being distorted while it is being drawn out by the drawing punch.

25 The split nuts 26, when used, are adjusted upon the screwthreaded rods 16, so as to permit the springs 30 to hold the shell gripped between the sleeve 20 and the stationary die 22 to the best advantage. 30 The continued descent of the crosshead forces the drawing punch through the die, to draw out the shell, and the bars 9 slide vertically over the rods 10. When the crosshead is raised the bars 9 engage with the 35 nuts 14, and raise the sleeve to its original position so that another shell can be inserted under it.

The supporting and pressing action of the sleeve inside the shell, enables the shell 40 to be drawn out successfully to a much greater extent at a single stroke, than is possible when no such sleeve is provided, and the shell is formed with a smooth surface and is free from cracks and wrinkles.

45 What I claim is:

1. The combination, with a single-acting press provided with a stationary die, and having a slidable crosshead arranged above the die, and a drawing punch secured to the said crosshead; of an attachment comprising a sleeve holder arranged between the said crosshead and die, a sleeve secured to the sleeve holder and encircling the said punch, suspending rods secured to the sleeve holder, a support for said rods secured to the crosshead and provided with openings for the said rods to slide in, nuts secured on the rods above their said support and affording a means for adjusting the sleeve 55 vertically with relation to the punch, and means for pressing the said sleeve down-

wardly upon the work while the punch is drawing it out, said means being suspended from the said sleeve holder.

2. The combination, with a press having 65 a stationary bed and die, said press having also a slidable crosshead and drawing punch; of an attachment comprising a sleeve holder arranged between the said crosshead and die, a sleeve secured to the sleeve holder and encircling the said punch, suspending rods for the sleeve holder, a support on the crosshead provided with openings for the suspending rods to slide in, nuts secured on the said rods above the said support and 70 affording a means for adjusting the sleeve with relation to the punch, rods secured to the sleeve holder and sliding in holes in the said bed and provided with nuts on their lower end portions, and springs encircling 75 the last said rods and arranged between their said nuts and the bed and operating to press the said sleeve on the work while the punch is drawing it out.

3. The combination, with a press having 85 a stationary bed and die, said press having also a slidable crosshead and drawing punch; of a sleeve holder arranged between the crosshead and the press bed, a sleeve secured to the sleeve holder and encircling 90 the punch, supporting rods secured to the sleeve holder and slidably connected with the crosshead and permitting the sleeve to slide downwardly with the punch during the first part of its stroke, rods secured to 95 the crosshead, adjustable stop nuts screwed on the last said rods and arranged above the press bed, and springs connected to the last said rods and operating to press the sleeve on the work while the punch is drawing it 100 out.

4. The combination, with a press having 105 a stationary bed and die, said press having also a slidable crosshead and drawing punch; of a sleeve holder arranged between the crosshead and the press bed, a sleeve secured to the sleeve holder and encircling the said punch, supporting rods secured to the sleeve holder and slidably connected with the crosshead and permitting the sleeve 110 to slide downwardly with the punch during the first part of its stroke, rods secured to the crosshead and slidably in holes in the press bed, adjusting nuts screwed on the lower end portions of the last said rods, 115 and springs arranged between the said nuts and the press bed and operating to press the said crosshead and sleeve downwardly.

In testimony whereof I have affixed my signature.

OTTO JOHN BOETTCHER.
